SHANK STIFFENER FOR SHOES

Charles H. Grimshaw, Kalamazoo, Mich.

Application March 1, 1950, Serial No. 147,038

4 Claims. (Cl. 36—76)

1

This invention relates in general to a shank stiffener for a shoe having a heel, and more specifically to a type thereof securable to the bottom of the shoe sole, and having adjustable means for regulating the amount of support.

It is a well established fact that the shank of an average shoe worn by a relatively heavy person will break down after a short period of wear. Once the shank in a shoe is broken down or flattened the shoe not only becomes uncomfortable, but also may permit injury to the arch of the person wearing the shoe.

Many attempts have been made to re-enforce the shanks of shoes with various types of built-in, or insertable, arch supports and shank stiffeners. While these supports have afforded some comfort for the average weight person, none of them allow for regulation or adjustment of the amount of support according to that needed by the wearer. Further, few supports will stand up under the constant strain exerted by the weight of a heavy individual.

Still further, persons with weak arches often find greater comfort if the amount of support can be regulated to their particular needs, which regulation is not convenient with the conventional form of support.

Accordingly, a primary object of this invention is the provision of a shank stiffener with adjustable means for regulating the amount of support to the needs of the wearer of the shoe.

A further object of this invention is the provision of an adjustable shank stiffener that may be secured to the bottom of the shoe sole.

Another object of this invention is the provision of a shank stiffener that will support the shank of a shoe that is worn by a person of relatively heavy weight.

A further object of this invention is the provision of an adjustable shank stiffener that is simple to adjust and inexpensive to manufacture, and which can be mounted on a standard shoe.

Other objects and purposes of this invention will be apparent to those who are familiar with this type of device upon examining the accompanying drawings and reading the following disclosure.

In carrying out the above objects of my invention I have provided a shank stiffener having a double leaf spring secured to a base plate. An adjustment plate with an adjustment screw is positioned at one end of said double leaf spring and is secured in position by means of a saddle member which is secured to said base plate.

2

In the drawings:

Figure 1 is a side elevation view of my invention as applied to the sole of a shoe.

Figure 2 is a top plan view of the base plate.

Figure 3 is a top plan view of my invention with an alternate type spring shown in broken lines.

Figure 4 is a sectional view taken along line IV—IV of Figure 3.

Figure 5 is a sectional view taken along line V—V of Figure 3.

Figure 6 is a section taken on an enlarged scale along line VI—VI of Figure 3.

Figure 7 is an oblique view of the adjustment plate.

Construction

As shown in Figures 2, 3, 4, and 6 the shank stiffener 10 comprises a T-shaped base plate 11, a double leaf spring 12 with leaves 13 and 13a, a saddle member 14 and an adjustment plate 15.

In describing the invention, the terms "forwardly" and "rearwardly" will refer to the directions toward the toe or toward the heel of the shoe, respectively.

The base plate 11 (Figures 2, 4 and 6) is T-shaped having a central portion 16 with flanges 17 and 17a extending sidewardly perpendicularly therefrom at the rearward end 18 thereof.

A pair of ears 19 and 19a extend sidewardly from said central portion 16 at the forward end 20 thereof.

The double leaf spring 12, which is made of a strong but flexible material, such as spring steel, has an upper leaf 13 of substantially the same length and width as the central portion 16. The lower leaf 13a differs from the upper leaf 13 in that it is longer than the plate 11. The double spring 12 is positioned on the plate 11 so that its rearward end 21 (Figure 6), lies on top of

and is aligned with the rearward end 18 of the plate 11. The spring 12 is secured to the base plate 11 at its forward end 20 by the ears 19 and 19a which are folded over the leaves of spring 12, and abuts at its rearward end an ear 23 which extends perpendicularly from the rear end 18 of the plate 11 (Figure 6).

The saddle member 14 (Figure 5) has a raised center portion 24, with flanges 25 and 25a extending sidewardly therefrom, and is positioned with respect to said base plate 11 so that its rear end 26 (Figure 6), lies above and is substantially aligned with the rear end 18 of the base plate 11 and the rear end 21 of the double leaf spring 12. The center portion 24 has a recess 27 (Figures 4 and 5), along its lower portion that is adapted to

3

straddle the double leaf spring 12 when the saddle member 14 is secured to the base plate. The saddle member is attached to the base plate by means of the flanges 17 and 17a, which are folded over the flanges 25 and 25a of the saddle member.

The adjustment plate 15 (Figure 7), which may be made of aluminum with highly rigid characteristics, is substantially rectangular in shape and has two upwardly extending stop bosses 34 and 35 secured to the upper surface thereof near its rear end 33. A threaded hole 37 (Figures 6 and 7), is provided through the plate 15 between said bosses 34 and 35 for reception of an adjustment screw 36. The adjustment plate 15 is smaller in length and width but greater in thickness than the base plate 11.

The raised center portion 24 of the saddle member forms a channel 29 to slidably receive and straddle the adjustment plate 15 when said plate is positioned on the double leaf spring 12.

A recess 31, in the end 26 (Figure 6), of the raised center portion 24 of the saddle 14, extends slightly more than half way through said member, and is shaped to slidably receive the bosses 34 and 35 on the adjustment plate 15.

The walls 38, 38a and 38b of the recess 31 and channel 29 (Figures 3 and 4), are beveled slightly and the sidewalls 39, 39a (Figure 7), of the adjustment plate 15 and the front walls 40 and 40a of the bosses 34 and 35 are beveled correspondingly to form a dovetail joint between saddle member 14 and adjustment plate 15.

The notch 39 (Figure 3), which is cut into the end wall 38b of the recess 31, is adapted to receive the head of the adjustment screw 36.

The double leaf spring 12 specifically described herein is only one of many that may be used in this invention. Other types of springs may be employed in accordance with the amount of support desired. For example, the size of the leaves 13 and 13a may be extended, as illustrated by the alternate form 42 shown by the broken line in Figure 3.

The shank stiffener 10 is secured to a shoe, adjacent to the heel 44, by screws 45 and 45a extending through the sole 43, the flanges 25 and 25a of the saddle member 14, and the flanges 17 and 17a of the base plate 11. By tightening appropriate nuts on the said screws 45 and 45a, the shank support 10 is snugly secured against the arch of the shoe, as shown in Figure 1, thereby producing an initial tension in the double leaf spring 12. The support 10 is now ready for operation.

Operation

The adjustment plate 15, which is slidable in the recess 31 may be secured in any desired position by tightening the adjustment screw 36.

When the shoe is worn, the weight of the wearer produces a downward force on the shank of the shoe. The double leaf spring which is held in tension exerts an upward force on the shank of the shoe, thus tending to counteract the said downward force and thereby preserving the shoe's original shape.

The amount of support furnished by the shank stiffener may be regulated by sliding the adjustment plate forwardly or backwardly and by appropriate adjustment of the screw 36.

When the adjustment screw 36 is tightened, the threaded end of the screw will move toward the leaf spring 12 until it contacts the lower surface of the spring leaf 13. Once contact is established between the screw 36 and the spring

4

leaf 13, further tightening of the screw will tend to urge the rearward end 33 of the adjustment plate away from the leaf spring 12.

The saddle member 24, which straddles the adjustment plate 15 forwardly of the screw 36, prevents movement of the straddled portion of the adjustment plate away from the leaf spring 12 and thus acts as a fulcrum producing movement of the forward end of the adjustment plate 15 toward the leaf spring when the rearward end 33 of the plate 15 is urged away from the shank of the shoe.

Since the forward end of the adjustment plate 15 is in contact with the leaf spring 12, the force imposed upon the forward end of the adjustment plate will also be imposed upon the leaf spring thus urging it against the shank of the shoe.

The amount of support may be further regulated by moving the adjustment plate 15 forwardly, thus adding more support to the double leaf spring 12.

The amount of support furnished by the shank stiffener 10 may further be varied by employing different size leaf springs, such as the alternate leaf 42 shown in Figure 2. By using a larger leaf the force exerted upon the shank may be more widely distributed allowing for lesser unit pressure and thus more comfort.

Although the above mentioned drawings and description apply to one particular preferred embodiment of the invention, it is not my intention, implied or otherwise, to eliminate other variations or modifications which do not depart from the scope of the invention unless specifically stated to the contrary in the hereinafter appended claims.

I claim:

1. In a shank stiffener securable to the sole of a shoe adjacent to the heel thereof, the combination: a base plate; a saddle member secured to said base plate near one end thereof, said member having a raised portion with recess in one edge thereof; a flat spring disposed between said base plate and the raised portion of said member, said spring being secured to said base plate; an adjustment plate disposed between said spring and the raised portion of said saddle; and a screw through said adjustment plate, near one end thereof and disposed within said recess; whereby movement of said screw effects a variation in the pressure between the spring and the end of the adjustment plate remote from the screw.

2. In a shank stiffener securable to the bottom of the sole of a shoe adjacent to the heel thereof, the combination comprising: a base plate having a pair of sidewardly extending flanges near one end thereof; a double leaf spring secured upon, and extending beyond the other end of, the base plate; an elongated saddle member crosswise of said base plate and having a raised portion intermediate its ends straddling said spring, said saddle ends being secured to said flanges, and said raised portion having a notch adjacent to said spring and a recess along the edge thereof adjacent to said base plate one end; an adjustment plate slidably extendable through said notch, said adjustment plate having a stop means on one side and near one end receivable within said recess; and an adjustment screw extending through said one end of said adjustment plate for engagement with said spring; whereby movement of said screw effects a variation in pressure between the

spring and that end of the adjustment plate remote from the screw.

3. In a shank stiffener securable to the sole of a shoe and adjacent the heel thereof, the combination: a base plate; a saddle member secured to said base plate near one end thereof, said member having a raised portion and means defining an opening through said raised portion; a flat spring disposed between said base plate and the raised portion of said member, and means securing said spring to said base plate and an adjustable plate disposed between said spring and the raised portion of said saddle member; threaded means so associated with said adjustment plate and so disposed within said opening that movement of said threaded means effects a variation of pressure between the end of the adjustment plate remote from the screw and that portion of said spring contacted thereby.

4. In a shank stiffener securable to the bottom of the shoe sole and adjacent to the heel thereof, the combination comprising: a base plate having a pair of sidewardly extending flanges near one end thereof; a leaf spring secured along and extending beyond the other end of, the base plate;

10

20

25

an elongated saddle member positioned cross-wise of said base plate and in substantial register with said sidewardly extending flanges, said saddle member having a raised portion intermediate its ends straddling said spring, the ends of said saddle member being securable to said flanges, said raised portion having means providing an opening therethrough which means are disposed adjacent the raised portion thereof nearest said one end of said base plate; an adjustment plate slidably positioned between said leaf spring and said raised portion; threaded means associated with said adjustment plate and in register with said opening for moving that end of said adjustment plate which is closest to said one end of said base member a selected distance toward said raised portion on said saddle member, whereby movement of said threaded means thereby effects a variation of pressure between said spring and that end of said adjustment plate remote from said threaded means.
